UNITED STATES PATENT OFFICE.

LEWIS A. HAINES, OF COLUMBUS, OHIO.

BLADING FOR TURBINES.

977,300.

Specification of Letters Patent. Patented Nov. 29, 1910.

Application filed April 25, 1910. Serial No. 557,449.

To all whom it may concern:

Be it known that I, LEWIS A. HAINES, a citizen of the United States, residing at Columbus, in the county of Franklin and State 5 of Ohio, have invented new and useful Improvements in Blading for Turbines, of which the following is a specification.

This invention relates to turbines and more particularly to blading or bucket 10 means therefor.

One object of the invention is to provide a plurality of buckets assembled in flexible relation in predetermined lengths in the form of sections and to apply the said sections regularly around a carrying element in such manner that the individual sections may be readily removed when burned out or otherwise unfit for further use and replaced by a similar section without disturbing the 20 remaining sections or dismantling the turbine.

With this and other objects and advantages in view, the invention consists in the construction and arrangement of the several 25 parts which will be more fully hereinafter specified in preferred form.

In the drawings: Figure 1 is an elevation of a portion of a carrying element, partially in section, and showing the blades or buckets and space blocks therefor arranged in distinct groups or sections. Fig. 2 is a transverse vertical section through a portion of the structure as shown by Fig. 1. Fig. 3 is a detail perspective view of one of the 35 sections or groups of blades or buckets and space blocks shown assembled and ready for application to the supporting or carrying element.

In my companion application Serial 40 Number 557,448 filed of even date herewith, a plurality of blades or buckets 8 and space blocks or spacers 9 are described as being assembled in the form of a flexible bar and then inserted and secured in a blade or 45 bucket carrying element and secured against movement. In the said application the flexible bar composed of alternately arranged blades or buckets and space blocks is continuous around the carrying element, and in 50 order to repair or replace any of the buckets or blocks it is necessary to remove the entire series of buckets or blocks. For general purposes there would be no objection to this 55 complete removal of the series of buckets and blocks, but in some applications or uses portions of the series of the buckets or blocks

might be required to be replaced at comparatively frequent intervals, and in order to meet this contingency the organization embodying the present features of the invention has been devised and consists in assembling and applying the buckets and blocks in group sections so that any one of the sections can be removed and replaced by another similar section without disturbing or 60 dismantling the remaining sections.

The same essential features of the invention are embodied in this instance as in the organization disclosed by my companion application above noted, and consist of the 70 blade or bucket carrying element 5 having a channel or groove 6 with counter grooves 7 in the side walls. The blades or buckets 8 and the blocks or spacers 9 are similar in all respects to those disclosed in my companion 75 application and are respectively provided with openings 10 and 11 therethrough. In this instance, however, shorter strands or wires 12 are used and threaded through the alined openings 10 and 11 and the ends 80 thereof projected beyond the terminal blades or buckets and projected through and upset against the inner portion of the carrying element 5, the short flexible bars or sections composed of the blades or buckets and blocks 85 being tightened up before the ends of the wires 12 are secured. Between the ends of contiguous sections, blocks 14 are introduced and form wedges to additionally tighten the blades or buckets and space blocks embodied 90 in each section, the key blocks being in all respects similar to the blocks 9 except that they do not have openings formed therethrough. The ends of the wire 12 are forced into downwardly extending or depending 95 grooves 15 in the inner or base portions of the blades or buckets located at the contiguous ends of the sections, and by this means a full clearance is given for the introduction 100 of the blocks 14. After the wires 12 have been secured, a copper or other metallic calking or calking strip 16 is introduced in the channel or groove 6 and compressed, and the blocks 9 and 14 are swaged or compressed to cause portions of the said calking or strip 16 105 and the blocks to engage the grooves 7 and form keys as at 17 and 18, and to also close up any crevices that may be present between the contiguous portions of the blades or buckets and blocks.

In removing any one of the sections the calking or calking strip 16 will be cut out 110

along the said section and in some instances it may be preferred that the said strip be made in lengths corresponding to the section. After the removed section has been 5 repaired, it may be replaced and secured by the introduction of new copper calking or a new copper or analogous metal calking strip.

What is claimed is:

1. In a turbine, the combination with a supporting element having a circumferential channel, of a plurality of independent sections of blades prepared prior to their application to the supporting element and individually separable from said element, said 10 sections each consisting of motive agent engaging means having a stringer extending therethrough and under tension, and devices interposed between the contiguous ends of the sections and engaging a portion of the 15 terminals of the stringers thereof.
2. In a turbine, the combination with a supporting element having a channel, of a plurality of independent motive agent engaging sections individually applied to and 20 removable from said element and having individual stringers extending therethrough, the motive agent engaging means and stringers being tightened up and held in close assembled relation prior to their application 25 to the supporting element, and securing means interposed between the ends of the sections and between the sides of the latter and one wall of the channel of the supporting 30 element.
3. In a turbine, the combination with a supporting element, of a plurality of motive agent engaging sections applied to and removable from the element and having a flexible means extending through each section, 35 the extremities of the flexible means of the sections engaging portions of the supporting 40

element and serving as a part of the securing means for the sections, and means interposed between the sides of the sections and a portion of the supporting element to serve as 45 an additional securing means for said sections.

4. In a turbine, the combination with a supporting element, of a plurality of groups of blades or buckets independently applied 50 to and removable from the element and having a flexible means threaded therethrough prior to application of the groups of blades or buckets to the supporting element, the opposite extremities of the flexible means being 55 projected through the supporting element and serving as a portion of the securing means for the groups of blades or buckets.

5. A blade or bucket section for use with a plurality of similar sections on a turbine 60 consisting of a series of interfitting blades or buckets and space blocks between the inner extremities of the blades or buckets, and a flexible strand threaded through the blades or buckets and blocks and bent inwardly over 65 portions of the end blades or buckets.

6. A blade or bucket section for use with a plurality of similar sections on a turbine consisting of motive engaging members, and a flexible stringer threaded through the 70 members and bent against portions of the end members, the motive engaging members and stringer being tightened up relatively to each other prior to application to a turbine. 75

In testimony whereof I have hereunto set my hand in presence of two subscribing witnesses.

LEWIS A. HAINES.
